UNITED STATES PATENT OFFICE.

JOSEPH MITCHELL, OF JERSEY CITY, NEW JERSEY.

DESIGN FOR A REFLECTOR FOR ANNULAR BURNERS.

SPECIFICATION forming part of Design No. 25,321, dated March 31, 1896.

Application filed May 27, 1895. Serial No. 550,867. Term of patent 7 years.

To all whom it may concern:

Be it known that I, JOSEPH MITCHELL, of Jersey City, in the county of Hudson and State of New Jersey, have produced a new and original Design for Reflectors for Annular Burners, of which the following is a specification.

The accompanying drawing is a perspective view of a reflector embodying my design.

The leading features of my design consist in a cylindrical surface, capped or surmounted by a surface which is that of a conical frustum.

A designates the body portion of the reflector, which is cylindrical in general outline, and B the portion in which the reflector

terminates, this latter portion being of a shape resembling that of a frustum of a cone.

What I claim is—

The design for a reflector for an annular burner, consisting of a cylindric portion, and an end portion whose shape is that of a frustum of a cone, substantially as shown and described.

In testimony whereof I have signed my name to this specification in the presence of two subscribing witnesses.

JOSEPH MITCHELL.
